Attorney

UNITED STATES PATENT OFFICE.

WINFRED T. PARKIN, OF PROVIDENCE, RHODE ISLAND, ASSIGNOR TO THEODORE W. FOSTER & BRO. CO., OF PROVIDENCE, RHODE ISLAND.

FILLER FOR VANITY CASES.

Application filed December 8, 1928. Serial No. 324,693.

This invention relates to fillers for vanity cases, and more particularly to a filler used to control the egress of the loose powder from the vanity case.

5 The primary object of the invention is to provide a filler wherein the parts can be easily and quickly assembled without the use of solder or extraneous fastening means, and more particularly to enable the parts to 10 be assembled by a snap-like movement thereof thereby to hold the parts by frictional engagement.

In the drawings:

Figure 1 is a top plan view of the invention;

Figure 2 is a bottom plan view;

Figure 3 is a section on line 3—3 of Figure 1; and

Figure 4 is a similar section showing the 20 parts in the action of assemblage.

In proceeding in accordance with the present invention, a felt ring 1 is employed which latter engages about the periphery of a cup-like or circular depression 2 formed in 25 a metal disk 3, the cup having perforations as indicated at 4 in its bottom. As shown in the drawings the circumferential wall of the cup is under-cut or has outwardly flaring inner and outer faces. A bottom ring 5 30 is employed which is formed to snap over the outer or peripheral face of the cup 2 while a rotor 6 having perforations 7 is employed and which has a bevelled peripheral edge to seat within and to be rotatably 35 held by the inner circumferential flared face of the marginal wall of the cup. The rotor 6 has a finger engaging piece 8 which overlies the ring 3 and is further formed with a depressed teat 9 formed to engage in a curved 40 channel or a depressed part 10 that is formed in the bottom of the cup 2, so as to limit rotary movement of the rotor in bringing the openings 4 and 7 into and out of register.

45 In assembly and with the parts in the position of Figure 4, it will be noted that the felt ring 1 is first engaged with the disk 3 and the outwardly flared peripheral face of the marginal wall of the cup, following 50 which the bottom ring 5 is snapped into position over said wall of the cup, thus clamping the felt ring between the disk 3

and the bottom ring 5, following which the rotor is snapped into position as shown in Figure 3 and is rotatably held by the inner 55 circumferential face of the marginal wall of the cup. Thus the parts are easily and quickly connected and all extraneous fastening means eliminated.

Having thus described my invention what I claim as new and desire to secure by Letters Patent is:

1. A filler for the loose powder in vanity cases, composed of a felt ring, a disk having an undercut central circular depressed and 65 foraminated part, said felt ring being engaged about said depressed portion, a bottom ring engaged over said depressed part to clamp the felt ring to the disk, said depressed part further having a curved depression having end walls, a foraminated rotor in the depressed part engaged with the undercut thereof and rotatably held thereby and having a teat extending into the curved depression and a finger engaging piece overlying 70 the top of the disk.

2. A filler for the loose powder in vanity cases composed of a felt ring, a disk having an undercut central circular depressed and 80 foraminated part, said felt ring being engaged about said depressed portion, a bottom ring engaged over said depressed part to clamp the felt ring to the disk, and a foraminated rotor in the depressed part engaged with the undercut thereof and rotatably held 85 thereby.

3. A filler for the loose powder in vanity cases, composed of a felt or like ring, a disk having a foraminated cup-like center which latter extends through the opening of the 90 rim, a bottom ring frictionally engaged over the cup periphery to clamp the felt ring against the disk, said cup having a circular outwardly flared inner face and a foraminated rotor rotatably held in the cup by 95 engagement with said flared inner face.

4. A filler for the loose powder in vanity cases, composed of a felt or like ring, a disk having a foraminated cup-like center which latter extends through the opening of the 100 rim, a bottom ring frictionally engaged over the cup periphery to clamp the felt ring against the disk, said cup having outwardly flared inner and outer circumferential faces,

the bottom ring being held in place by the outer flared face, and a foraminated rotor in the cup rotatably held therein by the inner flared face.

5. A filler for the loose powder in vanity cases, composed of a felt ring, a disk having a central cup-like foraminated depression

having an outwardly flared periphery, a bottom ring engaged with said periphery of the cup-like depression and a rotatable control 10 in the cup for the foraminations thereof.

In testimony whereof I have hereunto signed my name.

WINFRED T. PARKIN.
